UNITED STATES PATENT OFFICE.

VIRGINIUS Z. CARACRISTI, OF BRONXVILLE, NEW YORK, ASSIGNOR TO LOCOMOTIVE PULVERIZED FUEL COMPANY, A CORPORATION OF DELAWARE.

PULVERIZED-FUEL-BURNING APPARATUS.

Application filed March 25, 1920. Serial No. 368,524.

To all whom it may concern:

Be it known that I, VIRGINIUS Z. CARACRISTI, a citizen of the United States, residing at Bronxville, county of Westchester, 5 and State of New York, have invented certain new and useful Improvements in Pulverized-Fuel-Burning Apparatus, of which the following is a specification.

This invention has reference to an improved apparatus of the character specified designed more particularly for application to an internally fired boiler of the "Scotch marine" type. The first of the objects which I aim to accomplish by this improvement is 15 the provision of a powdered fuel burning apparatus which will give economical and reliable results in this type of boiler, which will secure good combustion of the fuel, and at the same time an effective distribution and 20 application of the heat.

A further object of this invention is the provision of a burner mechanism of novel construction for use in association with the boiler apparatus referred to which burner 25 is so designed that it will not only facilitate the admixture of the incoming fuel and the induced air which is added thereto, but will also provide for a whirling and gradually expanding action of the fuel and air as it 30 passes to the interior of the boiler.

A further object of the invention is the provision of a burner of the type specified which can be readily drawn back from the boiler to provide convenient access for inspection or repairs.

The above, as well as such other objects as may hereinafter appear, I obtain by means of a construction which I have illustrated in preferred form in the accompanying drawing, wherein:

Fig. 1 is an end view of a Scotch marine boiler of the internally fired type having my improvements applied thereto.

Fig. 2 is a longitudinal sectional view

45 through the boiler showing more especially the mounting of the removable burner device.

Fig. 3 is a section on the line 3—3 of Fig. 2.

50 The boiler as shown consists of a shell 1 having three corrugated flues 2, 3 and 4 with the connecting chamber 5, a series of tubes 5^a, and stack 6 arranged as is customary in apparatus of this character.

55 The tubes 5^a connect the chamber 5 with the

stack 6 and it will be understood that any suitable number are provided although two only are shown in the drawing in order to avoid confusion.

Against the outer end of the central corrugated flue or tube 3, I have shown a housing 7, having a refractory lining 8 and provided with a clean-out door 9 which also has air inlet passages therethrough which may be controlled by means of a suitable damper 10, the housing 7 also having an inclined inlet passage at 11 which connects with the burner when the latter is in operative position as shown in Fig. 2.

The burner is composed of a tubular metal shell 12 which has a refractory lining therein constructed to register with the passage 11 along a plane 13 which is inclined to the vertical as shown.

The fuel supply pipe 14 is arranged to open into the burner at one side of the center plane thereof as shown in Figs. 1 and 3 and also in a direction at an angle to the longitudinal axis of the burner passage as a result of which the fuel discharged into the burner will flow tangentially with respect to the interior surface of the burner and will set up a helical whirling motion and, at the same time, will expand as it descends or progresses toward the passage 11 by virtue of the conical or tapered shape of the interior of the burner and this will facilitate the mixing of the fuel and the induced air which enters through the upper end past the damper 15 which is provided with suitable fastening means 16 whereby to regulate the degree of opening.

The burner is mounted upon rollers 17 carried by tracks 18 supported adjacent to the furnace in position to permit the burner to be rolled away from the passage 11 so as to allow ready inspection of the burner or its parts as well as of the interior of the casing 7 and tube 3.

Additional auxiliary air inlets may be arranged on either side of the center of the burner tube as shown at 19, these being controlled by doors or covers 20 which, as desired, may be set to any degree of opening.

I claim:

1. A powdered fuel burning apparatus having in combination a casing having a chamber for cooperation with a boiler, a burner constructed to register with the inlet to said chamber, said burner having its

interior of gradually increasing dimension toward the chamber and fuel inlet means entering the burner at an angle to produce a whirling motion of the incoming fuel.

5. 2. A powdered fuel burning apparatus having in combination a casing having a chamber for cooperation with a boiler, a burner constructed to register with the inlet to said chamber, said burner having its interior of gradually increasing dimension toward the chamber and fuel inlet means entering the burner at an angle to produce a whirling motion of the incoming fuel, and means for inducing additional air to the stream of fuel within the burner.

3. In a boiler of the Scotch marine type, the combination of structure to be applied thereto for the adaptation of the boiler to the burning of pulverized fuel, said structure comprising a chamber having an outlet designed to be placed in communication with the inlet opening to a flue of the boiler with its axis substantially alined with the axis of the flue, said chamber also having an inlet, a burner discharging into the chamber through said inlet and at an angle with respect to the axis of the chamber, and a fuel inlet tangentially discharging into the burner and at an angle with respect to the axis of the burner, said burner flaring outwardly from the fuel inlet to the chamber.

4. In a boiler of the Scotch marine type, the combination of structure to be applied thereto for the adaptation of the boiler to the burning of pulverized fuel, said structure comprising a chamber having an outlet designed to be placed in communication with the inlet opening to a flue of the boiler with its axis substantially alined with the

axis of the flue, said chamber also having an inlet, a burner discharging into the chamber through said inlet and at an angle with respect to the axis of the chamber, and a fuel inlet discharging into the burner, said burner flaring outwardly from the fuel inlet to the chamber.

5. In an internally fired boiler, the combination of structure to be applied thereto for the adaptation of the boiler to the burning of pulverized fuel, said structure comprising a chamber having an outlet passage designed to be placed in communication with the inlet opening to a flue of the boiler and an inlet passage arranged to obliquely discharge the fuel into the flue, said inlet passage flaring outwardly in the direction of the flue, and means for introducing fuel under pressure at the smaller end of the inlet passage tangentially with respect to the wall of said passage.

6. In an internally fired boiler, the combination of structure to be applied thereto for the adaptation of the boiler to the burning of pulverized fuel, said structure comprising a chamber having an outlet passage designed to be placed in communication with the inlet opening to a flue of the boiler and an inlet passage arranged to obliquely discharge the fuel into the flue, said inlet passage flaring outwardly in the direction of the flue, and means for introducing fuel under pressure at the smaller end of the inlet passage tangentially with respect to the wall of said passage and at an angle with respect to the axis of said passage.

In testimony whereof, I have hereunto signed my name.

VIRGINIUS Z. CARACRISTI.
